PRINT BLOCK

Thomas Pesci, Raritan, N. J.

Application May 28, 1936, Serial No. 82,196

5 Claims. (Cl. 101—401.1)

My invention relates to improvements in print blocks for block printing machines for printing linoleum, oil-cloth, felt base floor coverings and the like, and particularly relates to print blocks having parallel kerfs formed in the printing surface and lines extending transversely to the length of the kerfs.

Print blocks of this type are formed of wood and the parallel kerfs are cut in the printing surface of the block for retaining the paint for printing purposes. The pattern which is to be printed is formed upon the block by cutting away certain portions of the printing surface between the kerfs, and to assist in following the pattern, 10 parallel lines, which are known as scratch lines are formed upon the printing surface and arranged transversely to the length of the kerfs. Great difficulty has heretofore been experienced in following the scratch lines, when cutting the block, as said lines are very faint and nearly 15 illegible.

The object of my invention is to provide a print block with scratch lines which are readily visible and legible, so that the lines may be followed 20 when cutting the printing surface of the block.

A further object is to provide scratch lines upon the block with distinctive coloring material upon the lines for making them legible.

A further object is to provide certain of the 25 scratch lines with additional distinctive material, relatively to the intervening lines, to form guide lines at given intervals.

A further object is to provide guide lines extending parallel with the kerfs to facilitate 30 in counting the kerfs.

A further object is to construct a print block with distinctive transverse guide lines arranged to 35 form squares of uniform size and embracing given numbers of the scratch lines and kerfs, whereby the scratch lines and kerfs may be readily counted when cutting the printing surface of the block.

Referring to the accompanying drawing; Fig. 1 is a plan view of a portion of a print block showing 40 the printing surface thereof and embodying my invention.

Fig. 2 is a perspective view of a portion of a print block as shown in Fig. 1.

In the drawing, in which like reference characters refer to like parts, 5 represents a print block which is formed of laminated wood. The standard size of the print block is nineteen inches in width, two inches in thickness, and six to nine feet in length. The printing surface 6 of the 45 block is provided with parallel kerfs 7, which ex-

tend transversely to the length of the block. The kerfs vary in size in different blocks so that the portions of the printing surface of the block located between the kerfs will be of different widths, depending upon the design to be formed by removing portions of the surface of the block between the kerfs, whereby the remaining portions will form the printing surface when the block is completed.

Longitudinal scratch lines 8 are applied to the printing surface, in a manner well known in the art, to assist in cutting the block according to a pattern. The scratch lines vary in number per inch corresponding to the lines upon the pattern to be followed in cutting the printing surface of 15 the block.

A novel feature of my invention is to provide a print block with material 12 superimposed upon the scratch lines 8 for making them more legible. The material 12 which is applied to the scratch 20 lines may be ink, or paint, of any color contrasting with the color of the printing surface of the block.

Another novel feature of the invention is to construct the print block with guide lines 14 and 25 15, consisting of the material 12 and contrasting in color to the surface of the print block.

The guide lines 14 are superimposed upon certain of the scratch lines at intervals of one inch and form guide lines for assisting in counting the 30 scratch lines. The lines 14 are formed by applying a greater quantity of the material 12 upon certain of the scratch lines which are located one inch apart.

The guide lines 15 extend parallel with the 35 kerfs 7. The lines 15 are formed of the material 12 which is applied to form the lines 15 upon the portions of the printing surface located between certain of the kerfs 7, at intervals of one inch 40 throughout the length of the block. The guide lines 15 are of great assistance in counting the kerfs when following a pattern.

The guide lines 14 and 15 extend transversely to each other and are arranged throughout the entire surface of the block in the form of squares, 45 representing square inches. The squares formed by the lines 14 and 15 assist in following the pattern which is to be followed when cutting the printing surface of the print block.

My invention involves a new and useful result 50 in print blocks, comprising scratch lines which are legible, guide lines which facilitate in counting the scratch lines and in counting the kerfs, and squares formed by said guide lines which 55 facilitate in following a pattern.

My improved print block has been found to provide a great saving of time and labor in cutting the printing surface of the block. Print blocks heretofore have been provided with scratch lines which were nearly illegible and they were not provided with any guide lines to facilitate in counting the scratch lines and the kerfs. My improved print block is constructed with scratch lines which are legible and the guide lines form 10 squares, representing square inches, throughout the entire printing surface of the block which are of great assistance in transferring a pattern to the print block.

I claim:—

- 15 1. A print block for block printing machines, comprising a printing surface upon the block, said printing surface having parallel kerfs formed therein, parallel scratch lines upon said surface and intersecting the kerfs, and means upon said 20 scratch lines for adding a contrasting appearance thereto relatively to the printing surface for increasing the legibility of said lines.
- 20 2. A print block for block printing machines, comprising a printing surface upon the block, said printing surface having parallel kerfs formed therein, parallel scratch lines upon said surface and intersecting the kerfs, and contrasting mate- 25

rial upon the scratch lines for increasing the legibility of said lines.

3. A print block for block printing machines, comprising a printing surface upon the block, said printing surface having parallel kerfs formed therein, parallel scratch lines upon said surface and intersecting the kerfs, and coloring material upon said scratch lines for making the latter visible. 5

4. A print block for block printing machines, comprising a printing surface upon the block, said printing surface having parallel kerfs formed therein, parallel scratch lines upon said surface and intersecting the kerfs, and contrasting material upon certain of said scratch lines located at 15 spaced intervals upon the printing surface. 10

5. A print block for block printing machines, comprising a printing surface upon the block, said printing surface having parallel kerfs formed therein, parallel scratch lines upon said surface 20 and intersecting the kerfs, contrasting material upon said scratch lines for making the latter visible, and certain of said scratch lines located at spaced intervals having a relatively greater amount of said material thereon than the intervening scratch lines. 25

THOMAS PESCI.
